BEDRAIL

Ludowicus Michl and Gabriella Michl, Vienna,
AustriaApplication June 28, 1935, Serial No. 28,967
In Austria August 14, 1934

1 Claim. (Cl. 5—296)

This invention relates to bed rails and its primary object and purpose is to provide the bed rail with fastener means by which the bed rail may be fixed very positively and securely yet detachably to the end members of the bed. The invention consists in novel constructions and arrangements of parts for very practically and effectively attaining the ends stated in a better manner than heretofore.

10 In the known bed rails with fasteners of this kind the latter consist either of hooked members adapted to be loosely connected with pins or of angle irons provided with slots by which they are placed onto screw bolts. In the case of angle irons it is necessary to provide for a mortise hole being cut in the end members of the bed or to provide for a clearance between the end member and the rail of the bed, so that the connection is very loose. At the least shaking the bed creaks 15 and sufficient room is present for the nesting of vermins. The screw bolts of the angle irons adapted to be clamped render difficult the attachment of the holed angle irons and their nuts extend into the bedding, so that the same is 20 easily damaged. Further in the known bed rail fasteners, the bed rails must be connected in succession with the head-end as well as with the 25 foot-end of the bed.

By the bed rail according to the present invention, these drawbacks are removed in that a T-shaped forked member and a T-shaped hooked member are independently from one another secured to the end face and to the top face and bottom face respectively of the bed rail and extend 30 beyond the same at the top side and bottom side respectively of said rail and, when fitting up the parts of the bed, at first the said forked member is hooked into a nut screw at the bottom of the end member of the bed and thereafter the said 35 hooked member is hooked from the side onto a nut screw at the top of the end member of the bed and now the nuts of said screws are tightened, so that the bed rails are fixed to the said end members without any clearance.

40 Thereby the bed rail fastener on the one hand does not depend on the depth of the bed rail. It can be manufactured in a single size and can be fixed without the necessity of arranging a mortise hole and on the other hand it does not lie 45 within the range of the bedding so that the latter cannot be damaged. Further the parts of the bed are more readily fitted together or taken apart in view of the successive connection of the forked member and of the hooked member with 50 the bottom and top bolts respectively.

55 One mode of carrying out the present invention is illustrated perspective in the drawing.

Fig. 1 is a perspective view of my device applied to the end of a bed rail.

Fig. 2 is a perspective view on a smaller scale showing my device securing a bed rail to a head board.

Fig. 3 is a perspective view of a detail.

The bed rail fastener consists of a T-shaped forked member 3 and a T-shaped hooked member 4. The flat side of the forked member 3 and of the hooked member 4 are secured independently from one another to each end face of the bed rail 2 in such a manner, that the forked member 3 extends beyond the bottom edge of the bed rail, while the hooked member 4 projects beyond the top edge thereof. Screw-threaded bolts 5 provided with nuts 7 are secured to the head-end as well as to the foot-end of the bed in accordance with the position of the forked member 3 and of the hooked member 4 on the bed rails. The members 3 and 4 are embedded and have 20 their faces in the plane of the end face of the bed rail 2 and are secured to the top side and bottom side of the bed rail by means of their branches 6.

The bed is erected in the following manner:— 25 At first the forked members 3 of the bed rail 2 are placed onto the bottom screw threaded bolts 5 of the head-end and of the foot-end of the bed, so that the bed rail can be turned towards the screw threaded bolts 5 at the top whereby the 30 bolts at the bottom act as pivots. Now by slightly lifting the bed rail, the hooked members 4 can be hooked onto the screw bolts at the top, so that the bed rail is carried by the same in the correct position. In this position of the bed rail, 35 the nuts are tightened and thereby the front faces of the bed rails the forked members and the hooked members are tightly pressed without any clearance onto the head-end and foot end of the bed. When unscrewing the nuts, the bed can be 40 taken to pieces by lifting and turning the bed rail away from the head-end and foot end of the bed.

What we claim is—

Bed rail comprising in combination a rail, a T-shaped member secured with its web on the 45 top face of said rail and with one of its flanges on the end face of said rail, a hook formed on the other of said flanges and projecting above said top face of said rail and opening from the side of the rail, a second T-shaped member secured 50 with its web on the bottom face of said rail and with one of its flanges on said end face of said rail, and a vertical slot in the other flange of said second T-shaped member to form a forked flange which projects below the said bottom face of 55 said rail.
